(57) **CLAIM**

The ornamental design for a combination odor absorber and pest deterrent, as shown and described.

DESCRIPTION

FIG. 1 is a front perspective view of a combination odor absorber and pest deterrent with the doors shown in an open position, showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof; and,

FIG. 8 is a front perspective view with the doors shown in a closed position.

The dashed lines indicate boundary areas and form no part of the claimed design.
